Primary Examiner—Doris V. Coles*Assistant Examiner*—Catherine R. Oliver*Attorney, Agent, or Firm*—Jacobson, Price, Holman & Stern, PLLC[57] **CLAIM**

The ornamental design for a bow forming tool, as shown and described.

DESCRIPTION

FIG. 1 is a front perspective view of the bow forming tool showing my new design;

FIG. 2 is a top plan view thereof;

FIG. 3 is a rear elevational view thereof;

FIG. 4 is a right side elevational view thereof;

FIG. 5 is a left side elevational view thereof; and,

FIG. 6 is a bottom plan view thereof.

The broken line showing of environment in FIG. 1 is for illustrative purposes only and forms no part of the claimed design.
